GUN RACK

Franklin J. Van Buren, San Antonio, Tex., assignor to Western Novelties Manufacturing Company, Inc., San Antonio, Tex., a corporation of Texas

Application May 17, 1957, Serial No. 46,213

Term of patent 7 years

(Cl. D33—3)

The figure is a perspective view of the obverse side of the gun rack.

The reverse side of the rack is plain and flat.

The dominant features of my design reside in those portions shown in full lines on the drawing.

I claim:

The ornamental design for a gun rack, as shown and described.
